(57) **CLAIM**

The ornamental design for a shower rod adaptor, as shown and described.

DESCRIPTION

FIG. 1 is a front elevational view of a shower rod adaptor showing our new design, the rear elevational view being a mirror image thereof;

FIG. 2 is a side view, taken from the left side of FIG. 1;
FIG. 4 is a side view, taken from the right side of FIG. 1;
FIG. 4 is a top plan view thereof; and,
FIG. 5 is a bottom plan view thereof.
